UNITED STATES PATENT OFFICE.

FOSTER F. HILLIX, OF CLEVELAND, OHIO, ASSIGNOR TO WHITE SEWING MACHINE COMPANY, OF CLEVELAND, OHIO, A CORPORATION OF OHIO.

MOTOR ATTACHMENT FOR SEWING MACHINES.

Application filed October 29, 1921. Serial No. 511,856.

To all whom it may concern:

Be it known that I, FOSTER F. HILLIX, a citizen of the United States, residing at Cleveland, in the county of Cuyahoga and State of Ohio, have invented a certain new and useful Improvement in Motor Attachments for Sewing Machines, of which the following is a full, clear, and exact description.

10 The present invention relates to a motor attachment for sewing machines, and has for its object to provide an attachment which does not require brackets to secure it to the sewing machine, and which can be readily applied to any existing machines. Further, 15 the invention aims to provide a construction wherein the motor does not add materially to the bulk or size of the head of the machine. Still further the invention aims to 20 provide an attachment wherein the motor is mounted at the end of the head and preferably is hung from the shaft of the head, the construction being such that a high speed motor may be utilized with reduction 25 gearing between the motor shaft and main shaft of the head.

The invention may be briefly summarized as consisting in certain novel details of construction, and combinations and arrangements of parts to be described in the specifications of parts to be described in the specification and set forth in the appended claims.

In the accompanying sheet of drawings showing the preferred embodiment of the invention, Fig. 1 shows in side elevation a 35 portion of the head of the sewing machine with part of the motor attachment in section; and Fig. 2 is an end view looking toward the left of Fig. 1, with parts broken away for the sake of clearness.

40 The head of the sewing machine includes a bed 10 and an arm 11 having the usual upright and horizontal portions, the arm being provided with a main operating shaft 12.

The motor for driving the machine is arranged at the end of the head, and in the present embodiment the shaft in the head is used as the motor support. It is desirable, however, that a high speed motor be utilized, and that suitable speed reduction be provided between the motor and shaft 12. For that reason the motor attachment includes a motor 13 which while supported from the shaft 12 is arranged below the latter, as clearly shown in Fig. 1. The frame or casting of the motor 13 is extended upwardly

where it is provided with a top portion 14 which is annular in form, and is concentric with respect to the axis of the shaft 12. At the center of the part 14 there is an inwardly extending hub 15 which is slipped onto 60 a sleeve 16 surrounding the shaft 12, and keyed thereto, which sleeve has an outwardly extending flange 17. The hub 15 is held in place up against the flange 17 by a screw 18 at the outer end of shaft 12.

The shaft 19 of motor 13 has a pinion 20 which drives an intermediate gear 21 supported in this instance on the casing of the motor, both the pinion 20 and intermediate gear 21 being on the inside of the motor casing, and the intermediate gear 21 drives a gear 22 which is concentric with respect to the shaft 12 and has a bearing on an annular shoulder 15^a of the boss 15 of the upper extension of the motor casing. The upper 70 annular part 14 of the upper extension of the motor casing has a flange which extends over the gear 22 so as to completely enclose it.

On the inner side of the gear 22 there is a 80 hand wheel 23 which is also concentric with respect to the shaft 12. This hand wheel has a portion 23^a which fits down onto and extends on the rear side of flange 17 which, as before stated, is a part of sleeve 16 keyed 85 to shaft 12. Likewise the hand wheel has an axially extending hub-like portion 23^b to which the gear 22 is secured by screws 24 or other means.

The hub-like portion 23 of the hand wheel 90 carries a sliding locking pin 25 by which the hand wheel may be locked to or released from shaft 12. This locking pin can be shifted by an outside button 25^a, and when moved to left hand position when viewed as 95 in Fig. 1, it fits into a notch in the periphery of flange 17 on sleeve 16, so that the hand wheel and shaft 12 turn in unison, but when the pin 25 is slipped to its right hand position, the motor will turn the hand wheel, 100 but not turn the shaft 12, whereupon the device may be used for bobbin winding purposes.

To prevent the motor revolving about the axis of shaft 12 when the motor is energized, 105 any suitable stop means is provided between the motor and lower part of arm 11, this stop means being here shown in the form of a holding pin 26, though other suitable holding means may be utilized if desired.

Thus it will be seen that the motor attachment is in the form of a unit hung from the operating shaft 12 of the motor head, but still, unlike the motors which are concentric with respect to the driving shaft, the present motor can be a high speed motor with its speed reduced by reducing gearing to the speed at which the shaft of the head is to be rotated. This permits a much higher efficiency than is possible with a motor which is mounted direct on the shaft of the head. The attachment can be readily applied to or removed from the shaft 12, and the construction is such that an attachment of this form can be applied to practically all existing machines, it being necessary only to remove the ordinary hand wheel and replace it with the motor attachment having a special hand wheel, such as that herein illustrated.

I do not desire to be confined to the exact details and arrangements shown, as changes may be made without departing from the spirit and scope of the invention; for example, it may be desirable to use a different form of driving means between the motor and shaft of the head than the gears here illustrated. Likewise, other changes may be made in the details of the construction.

Having described my invention, I claim:

1. In combination with a sewing machine head having an operating shaft extending therethrough, a motor supported by the head and arranged at the end thereof, with its driving shaft parallel to the shaft of the head but below the same.

2. In combination with a sewing machine head having an operating shaft, a motor at the end of the head, said motor being hung from said shaft but arranged below the same. 40

3. The combination with a sewing machine head having an operating shaft, of a motor attachment at the end of the head and supported by the shaft, said attachment comprising a motor with a speed reducing driving connection with the shaft of the head. 45

4. The combination with a sewing machine head having an operating shaft, of a motor attachment at the end of the head and supported by or hung from the shaft, 50 said attachment comprising a relatively high speed motor with a speed reducing driving connection with the shaft of the head, and said attachment including also a hand wheel through which the motor 55 normally transmits power to the shaft.

5. The combination with a sewing machine head having an operating shaft, a motor attachment at the end of the head and supported by or hung from the shaft, said 60 attachment comprising a relatively high speed motor with a speed reducing driving connection with the shaft of the head, and said attachment including also a hand wheel through which the motor normally transmits power to the shaft, and means by which the hand wheel may be connected to and disconnected from the shaft. 65

In testimony whereof, I hereunto affix my signature,

FOSTER F. HILLIX.
